UNITED STATES PATENT OFFICE

WILLIS O. PROUTY, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A MARQUISE

Application filed May 4, 1931. Serial No. 39,715. Term of patent 14 years.

To all whom it may concern:

Be it known that I, WILLIS O. PROUTY, a citizen of the United States, and a resident of the city of Hermosa Beach, in the county of Los Angeles and State of California, have invented a new, original, and ornamental Design for a Marquise, of which the following is a specification, reference being had to the accompanying drawings, forming part thereof.

Fig. 2 is an enlarged detail perspective of the upper part of the marquise, corresponding to the part included between lines 2—2 of Fig. 1; and

Fig. 3 is an enlarged detail perspective of the lower border of the marquise shown in Fig. 1.

I claim:

The ornamental design for a marquise substantially as shown.

WILLIS O. PROUTY.
